VENTILATOR DEVICE

Oscar F. Mueller, St. Louis, Mo.

Application August 24, 1935, Serial No. 37,633

8 Claims. (Cl. 98—43)

This invention relates to ventilator devices; and has special reference to ventilators of the type that are mounted in openings through walls and which include fans operating in a manner to exhaust fumes and vitiated air from the inside of rooms or buildings.

Objects of the invention are to provide an improved ventilator including a casing or shell comprising telescoping members which are preferably rectangular in end elevation or in cross-section, and which are designed and adapted to be built in a wall during the construction of the wall, the rectangular formation of the shell or casing facilitating the construction of the wall, and the telescoping arrangement making it possible to extend or reduce the length of the shell or casing in accordance with the thickness of the wall; to provide an improved louver device for attachment to the outer end of the shell or casing that will substantially prevent rain and other falling substances from entering the casing without substantially interfering with or obstructing the outward flow of air driven by the fan; to provide an improved support for the fan, and means whereby said support may be conveniently mounted in proper position within the inner portion of the shell or casing; to provide improved retainers and holders for the electric wires cord leading to the motor and for the connection for operating the switch controlling the flow of electric current to the motor; to provide improved means for expediting the proper location and placement of the motor and fan support within the shell or casing; to provide a finishing frame for engaging the inner surface of the wall and the inner end of the shell or casing whereby an appropriate pleasing effect is obtained; and to provide a circular door for opening and closing the inner end of the shell or casing.

Other objects should be readily apparent from the following description, reference being made to the annexed drawings, in which—

Fig. 1 is an outer end side elevation of the louver forming a part of my improved ventilator device.

Fig. 2 is a vertical longitudinal sectional view of the ventilator device approximately on the line 2—2 of Fig. 1.

Fig. 3 is an inner end elevation of the ventilator device.

Fig. 4 is a vertical cross-sectional view approximately on the line 4—4 of Fig. 2.

Fig. 5 is a vertical cross-sectional view approximately on the line 5—5 of Fig. 2.

Fig. 6 is an enlarged vertical longitudinal sectional view of a portion of the inner end of the shell or casing, the door therefor and the support for the fan motor.

Fig. 7 is an enlarged sectional view of the upper portion of the inner end of the ventilator device more clearly illustrating features of the invention.

Fig. 8 is a vertical cross-sectional view of a portion of the device including the support for the fan motor approximately on the line 8—8 of Fig. 7.

Fig. 9 is an enlarged vertical longitudinal sectional view of the ventilator device modified for embodiment in a relatively thin wall of wood or other material.

Fig. 10 is a vertical cross-sectional view of the support for the fan motor approximately on the line 10—10 of Fig. 9.

Fig. 11 is a sectional view approximately on the line 11—11 of Fig. 3.

In one embodiment of the invention, the shell or casing comprises an outer section 1 telescoping on the outer end portion of an inner section 2. The shell or casing thus provided is rectangular in cross-section, as clearly shown in Figs. 4 and 5, and the length of the section may be increased or reduced by relative telescoping adjustment of the sections 1 and 2. A louver device is attached to the outer end of the section 1 of the shell or casing by flanges 3 welded or otherwise attached to said section 1. The louver device is split and pressed to form integral outwardly and downwardly extended louvers 4 providing openings 5 through which air may be driven to the outside from within the room into which the ventilator device opens. The louver device substantially prevents rain and other substances from entering the shell or casing, and has along its lower margin a series of holes 6 through which any liquid may freely flow and be discharged from within the shell or casing. The inner end of the section 2 may be formed with an outwardly extended flange 7 engaging the inner surface of the wall 8 in which the ventilator device is mounted. The section 2 telescopes somewhat loosely into the section 1 so that any slight indentations or irregularities in the walls of either or both of said sections will not prevent the proper assembly thereof.

A rectangular frame or shell 9 is fitted loosely against the inner surfaces of the side and top walls of the section 2 and is supported by a number of springs 10 on the bottom wall of the sec-

tion 2 (Figs. 2, 4, and 5). A tubular casing 11 has its inner end attached to a rectangular wall 12 mounted in and welded or otherwise attached to the outer end of the shell 9, said wall 12 being provided with outwardly extended marginal flanges 13 for attachment to said shell 9. The wall 12 is provided with a circular hole 14 therethrough the margin of which is welded or otherwise attached to a laterally turned flange 15 on the outer end of the tubular section 11. The inner end of the tubular section 11 is mounted in an annular portion 16 forming a part of and connected with a finishing frame 17 by an annular bead 18 forming an abutment for the inner end of the tube 11. The outer portion of the finishing frame 17 is formed with a rectangular bead 19 the margin of which is telescoped on the inner end of the shell 9 and attached thereto by welding or otherwise. The edge of the bead 19 forms an abutment engaging the marginal portion of a rectangular frame 20 mounted around the inner end of the section 2 and appropriately shaped so that the outer edge of the frame 20 presses against the inner surface of the wall 8. A number of connecting rods 21 have their outer ends projecting through slots 22 formed through the inner end portions of arms 23 rigid with the section 2 and projecting from the corners toward the axis thereof. Nuts 24 are screwed on the threaded outer ends of the rods 21 against the arms 23, and the inner ends of said rods 21 extend through the frame 17 and have heads 25 seating in sockets 26 in connection with said frame 17. Thus, the structure comprising the tubular section 11, the wall 12 and the frame 17 is held in an assembled relationship in which the edges of the frame 17 are rigid with the section 2 and engage the finishing frame member 20 of the ventilator device.

Four retaining devices 27 are attached to the inner side of the tube 11, each retaining device having its outer marginal portion rigidly attached to the tube 11 and having its inner marginal portion curved in accordance with the curvature of the tube 11 and spaced therefrom. A support for the fan motor of the ventilator device has portions detachably engaging the retaining devices 27. As shown, said support may comprise a section of sheet metal formed to provide a supporting wall 28 having each end integrally connected with an outwardly extended wall 29 curving in accordance with the curvature of the tube 11 and having their ends slidably engaged between the retaining devices 27 and said tube 11. The supporting wall 28 has integral therewith two outwardly extended walls 30 the upper and lower ends of which engage and form supports for the curved laterally extended portions of the walls 29. Angular strengthening strips 31 are welded or otherwise attached to the curved walls 29 and to the walls 30. The upper wall 29 is formed with a hole 32 and with a channel 33 (Figs. 6, 7, and 8) to receive and support the electric wires cord (not shown) leading to the motor for supplying the necessary electrical energy. Similarly, the lower curved wall 29 is formed with a hole 34 and with a channel 35 through which a flexible actuator for the usual switch (not shown) for opening and closing the electric circuit to the motor may extend.

As stated, the support comprising the wall 28 and attached parts has detachable sliding engagement with the retaining devices 27 so that said support may be easily placed in and re-

moved from the tube 11. Abutments 36 for the outer ends of the walls 29 are attached to the tube 11 to stop the motor support in precisely the proper position when said motor support is slipped into the retaining devices 27.

A pair of members 37 and 38, which are approximately U-shaped in cross-section (Fig. 10), are telescoped on the upper and lower portions of the walls 30 and are indented to form detents 39 to engage in indentations 40 in the walls 30. The members 37 and 38 are spaced apart and the motor 41 extends and is supported between the adjacent ends of said members. The frame of the motor 41 is attached to the support 28 by removable and replaceable screw fasteners 42. The motor 41 drives a shaft 43 to which appropriate fan blades 44 are attached and which operate to drive the air outwardly through the louver device 4.

An annular frame 45 is removably mounted in the outer end of the tube 11 seating against the flange 15 and being of greater diameter than the diameter of the opening 14, so that said frame cannot pass through said opening. The upper portion of the frame 45 is received in a space between the flange 15 and a holding bracket 46 so that the upper portion of the frame cannot tilt or incline away from the flange 15. A spring 47 (Fig. 9) is attached to the lower portion of the frame 45 and presses against the inner surface of the lower portion of the tube 11 and yieldingly holds the lower portion of the frame against the flange 15. A handle element 48 is attached to the lower part of the frame 45 and affords means whereby the lower portion of the frame 45 may be moved inwardly away from the flange 15 to withdraw the frame from its mounting within the tube 11; but, of course, the frame 45 cannot be removed from the tube 11 while the fan mechanism including its support 40 remains in position in the tube 11. A screen 49 has its margin rigidly attached to the frame 45 in an appropriate manner, as by doubling the frame 45 upon itself and clamping the margins thereof upon the margin of the screen, as should be understood by reference to Fig. 7 of the drawings. This screen 49 prevents any substantial amounts of foreign substances, particularly solids, from entering the tube 11 from the outside, but does not seriously interfere with the effective operation of the fan to expel vitiated and other air from the room into which the ventilator device opens.

A circular inwardly dished door 50 has one side connected by a hinge 51 with the frame part 11, and has a marginal portion 52 that seats against said frame part 17 when the door is closed. The door 50 is formed with an annular groove 53 in which a sealing ring 54 of felt or other appropriate elastic material is firmly secured and retained by the dovetail formation of the walls of the grooves 53 (Fig. 7). When the door 50 is closed, the projecting part of the sealing ring 54 engages and seats in an annular angular groove 55 formed by the union of the frame parts 16 and 17. Thus, the opening to the inner end of the tube 11 is practically hermetically sealed when the door 50 is closed, thereby preventing dust and other foreign particles and substances from becoming deposited in the tube 11. Even if such particles assemble and lodge upon the outer surface of the screen 49, they will, to a large extent, be blown out when the fan is operated. The door 50 may be provided with a conventional latch device 56 for holding the

door closed, and with a knob 57 for manual engagement to open and close the door. The angular portions of the frame part 17 beyond the margin 52 of the door 50 may be pressed to form 5 ornamental and strengthening beads 58. Also, the upper and lower portions of the door margin 52 may be formed with grooves 59 communicating with the grooves 33 and 35, respectively, for the passage of the wires cord and switch operating connection (not shown). And a clip 60 may be attached to the upper bead 19 to support and hold the wires cord in proper position so that it will not become displaced or moved laterally and interfere with the closing of the door.

15 The construction may be varied within the scope of equivalent limits to adapt the device for mounting in the wall of a frame or wood building, or for other purposes. As shown in Fig. 9, the rectangular shell or casing 61 is the analog of the shell or casing section 1 and extends the full thickness of the wall 63 and beyond the outer surface of said wall. A frame 63 is mounted around the outwardly projecting end of the shell or casing 61 and seats against the outer surface of the wall 62, and a louver member 64 is attached to the outer end of the casing 61 and holds the frame 63 in position. Louver formations 65 on the member 63 provide openings 66.

30 The casing section 67 is the analog of the casing section 2 and has its top and side walls fitting loosely within the casing 61 and the bottom wall being supported by springs 68. Rods 69 have their outer ends screwed into sockets 70 supported by the louver member 64, and have their headed inner ends seated in the sockets 26 on the frame 17. The remaining elements and features of construction of the slightly modified device shown in Fig. 9 are the same as those already described, and like reference numerals are applied thereto. The principal difference between the modification shown in Fig. 9 and the construction previously described is in the arrangement of the rods 69 which connect directly with the louver member 64, the arms 23 being eliminated.

From the foregoing, it should be apparent that this invention attains all of its intended objects and purposes efficiently and satisfactorily. The parts and the assembly thereof are free from objectionable complications and the device may be manufactured and assembled and mounted in a wall at permissible and satisfactory cost. The structure may be varied within the scope 55 of equivalent limits in particulars other than those specifically suggested.

I claim:—

1. In a ventilator device adapted to form an opening through a wall, inner and outer casing sections telescoping one within the other, a louver device attached to the outer end of the outer section, a wall element within the inner section and spaced outwardly from the inner end thereof, an additional wall element attached to the inner end of said inner section, a tubular member engaged and supported by said wall elements, a support mounted transversely in said tubular member, means engaging and holding said support in said tubular member and leaving said support free for removal and replacement, and a motor attached to said support and having a shaft extending outwardly toward said louver device.

2. In a ventilator device adapted to form an opening through a wall, inner and outer casing

sections telescoping one within the other, a louver device attached to the outer end of the outer section, a wall element within the inner section and spaced outwardly from the inner end thereof, an additional wall element attached to the inner end of said inner section, a tubular member engaged and supported by said wall elements, a support mounted transversely in said tubular member, means engaging and holding said support in said tubular member and leaving said support free for removal and replacement, a motor attached to said support and having a shaft extending outwardly toward said louver device, and connections between said inner section and one of said wall elements holding said one wall element and thereby said tubular member in rigid relationship.

3. In a ventilator device of the character described, two rectangular casing sections telescoping one within the other for extending or shortening the length of the casing formed thereby as desired, a pair of wall elements supported within the inner end of one of said sections, a tubular member supported by said wall elements, arms rigid with one of said sections, rods connecting said arms with one of said wall elements, a motor supported in said tubular member, a fan operated by said motor, and a door hinged to one of said wall elements for opening and closing the inner end of said tubular member.

4. A ventilator device comprising inner and outer rectangular casing sections telescoping one within the other, a rectangular shell mounted within the inner end of the inner section, resilient means supporting said shell in said inner section, a wall element attached to the end portion of said shell beyond the adjacent end of said inner section, an additional wall element mounted in said shell and spaced from said first named wall element, a tubular member supported by said wall elements, arms projecting from said inner section, rods engaging said arms and one of said wall elements and holding said shell in said inner casing section, and means for supporting and operating a fan in said tubular member.

5. A ventilator device comprising a casing adapted to be supported in an opening in a wall, a shell mounted in said casing, wall elements supported by said shell, a tubular member supported by said wall elements, means removably holding said wall elements and said tubular member in said casing, a support extending transversely across said tubular member, a motor attached to said support in said tubular member, a fan operated by said motor, a screen, and means supporting said screen in connection with said tubular member beyond said fan.

6. A ventilator device comprising a casing, a shell mounted in the inner end of said casing, a tubular member in and spaced from said shell, wall elements engaging said shell and said tubular member and closing the space between them, retaining devices attached to the inside of the tubular member, a support extending transversely within said tubular member and having sliding withdrawable and replaceable engagement with said retaining devices, and blower mechanism supported by said support in said tubular member.

7. A ventilator device comprising a casing, a shell removably mounted in the inner end of said casing, a tubular member within and spaced

from said shell, and being removable therewith, wall elements connecting said shell and said tubular member and closing the space between them and supporting the tubular member in said shell, one of said wall elements having detachable connection with said casing, and blower mechanism mounted in said tubular member and withdrawable therewith from said casing when said shell and said tubular member are withdrawn.

8. A ventilator device comprising a casing, a shell removably mounted in the inner end of said casing, springs yieldingly supporting said shell in said casing, a tubular member within and spaced from said shell, and being removable therewith, wall elements connecting said shell

and said tubular member and closing the space between them and supporting the tubular member in said shell, one of said wall elements having detachable connection with said casing, blower mechanism mounted in said tubular member and withdrawable therewith from said casing when said shell and said tubular member are withdrawn, arms within and rigid with said casing, and connections engaging said arms and holding said shell and said tubular member in said casing, and a door hinged to that one of said wall elements that has detachable connection with said shell for opening and closing said tubular member.

OSCAR F. MUELLER. 15
